COMBINED BROOCH AND LOCKET

Cornelius G. Bess, San Francisco, Calif.

Application June 6, 1950, Serial No. 10,390

Term of patent 7 years

(Cl. D45—19)

To all whom it may concern:

Be it known that I, Cornelius G. Bess, a citizen of the United States, residing at AF 32055126, 35th Ftr. Intcp. Group, 40 Ftr. Intcp. Squadron, A. P. O. 328, % Postmaster, San Francisco, California, have invented a new, original, and ornamental Design for a Combined Brooch and Locket, of which the following is a specification, reference being had to the accompanying drawing, forming a part hereof.

Fig. 1 is a front perspective view of a combined brooch and locket embodying my new design, the locket member being in a partially open position;

Figs. 2 and 3 are front and rear elevational views, respectively, of the combined brooch and locket;

Fig. 4 is a bottom plan view thereof with the locket member in wide open position; and

Fig. 5 is a side elevational view of the combined brooch and locket.

I claim:

The ornamental design for a combined brooch and locket, as shown.

CORNELIUS G. BESS.
